HAIR CLIPPER

Chester J. Mazzoni, 22701 Michigan Ave.,
Dearborn, Mich.

Filed Dec. 17, 1958, Ser. No. 781,104

7 Claims. (Cl. 30—201)

This invention relates to hair clippers and, in particular, to hair clippers with hair length cutting adjustments.

One object of this invention is to provide a motor-driven self-operated hair clipper with a length-of-cut guide which is easily and efficiently used by a person for cutting his own hair without requiring the assistance or services of a barber, the device being adapted for ease of use in cutting hair at the back of the head, even though it cannot be seen directly by the user.

Another object is to provide a motor-driven self-operated hair clipper with a length-of-cut guide of the foregoing character wherein the guide includes a comb mounted on one arm of an angle bracket, the other arm of which is attached to one side of the clipper in such a manner as to be quickly and easily adjusted relatively to the clipper in order to vary the distance between the comb and the clipper cutters and thus to vary the length of cut of the hair.

Another object is to provide a motor-driven self-operated hair clipper with a length-of-cut guide wherein the clipper cutters and the comb are mounted parallel to one another and substantially perpendicular to the longitudinal axis of the clipper, the bracket for the comb being mounted on one of the side walls for sliding adjustment motion relatively thereto, so as to vary the distance between the comb and cutters in order to vary the length of the hair being cut.

Another object is to provide a motor-driven self-operated hair clipper of the foregoing character wherein the entire device including the clipper and the length-of-cut guide regulator are sufficient short in length to be held between the palm of the user's hand and his bent-over finger tips, thereby enabling the cutting operation to be conducted with a combing motion in a rapid and easy manner.

Another object is to provide a motor-driven self-operated hair clipper of the foregoing character wherein the angle bracket which holds the comb is adjustably attached to one side of the clipper by a yieldable detent device which normally holds the angle bracket and comb in fixed relationship to the cutters but which, when pushed or pulled with sufficient force overrides the detent device to enable the angle bracket to be moved relatively to the clipper, thereby enabling the comb to be moved toward or away from the cutters in order to vary the length of cut of the hair.

Other objects and advantages of the invention will become apparent during the course of the following description of the accompanying drawings, wherein:

Figure 1 is a side elevation of a motor-driven self-operated hair clipper, according to one form of the invention, with the position of the user's hand grasping the clipper shown in broken lines;

Figure 2 is a top plan view of the self-operated hair clipper shown in Figure 1;

Figure 3 is a left-hand side elevation of the self-operated hair clipper with the upper portion in section along the line 3—3 in Figure 2, to show details of the attachment

2

of the cutting guide and of the rapid-action detent device.

Referring to the drawings in detail, Figures 1 to 3 inclusive show a motor-driven self-operated cut-regulating hair clipper, generally designated 10, according to one form of the invention, as consisting generally of a motor-driven hair clipper 12 and an adjustable length of cut guide 14 adjustably attached to the clipper 12. The clipper 12 is of conventional construction with a casing 16 containing an electric motor (not shown) and a cable 20 connection 18 from which a twin conductor cable or so-called cord extends to a conventional plug (not shown) adapted to be inserted in an ordinary house lighting current outlet (also not shown). Fixedly mounted on and projecting from the forward end 22 of the casing 16 (Figure 1) is the shank 24 of a fixed cutter unit 26 having a multi-tined cutter 28 extending at right angles to the shank 24 and parallel to the forward end 22 and mounted in spaced relationship therewith.

Mounted in the space between the fixed cutter 28 and the casing end 22 and disposed parallel thereto is a multi-tined reciprocable cutter 30, the cutting tines 32 of the fixed cutter 28 being disposed in close proximity to the cutting tines 34 of the reciprocable cutter 30. The cutters 28 and 30 are thus disposed transversely to the casing 16. The fixed and movable cutters 28 and 30 collectively form a cutting head, generally designated 36, with a cutting nose 38 including the tines 32 and 34. The energization of the motor within the casing 16 from the cable 20 at the rearward end 40 of the casing 16 is controlled by a switch (not shown) actuated by a switch button 39 on the casing 16 near the thumb T of the user's hand H. The reciprocable cutter 30 is moved to and fro relatively to the fixed cutter 28 by being connected to an eccentric on the shaft of the driving motor within the casing 16 in a manner well-known to those skilled in the motor-driven hair clipper and shaver art. This internal mechanism is conventional and is beyond the scope of the present invention.

It is to be emphasized, however, that in order for the self-operated hair clipper of the present invention to be easily grasped in one of the user's hands and manipulated by the user so as to reach and clip all portions of his head including the back of his head, the casing 16 between the forward cutter end 22 and the rearward cable connection end 40 must be unusually short. The casing 16 for this reason is preferred to be laterally elongated or of excessive shortness, wider than it is long, in order to facilitate convenient grasping. In other words, the casing 16 is preferably laterally elongated, that is, shorter in a longitudinal direction between its opposite ends 22 and 40 than it is wide between its opposite sides 42 in order to enable it to be held in the palm P of the user's hand H between the thumb T and fingers F with the finger tips extending around the guide 14. This enables the hair to be cut preferably with a combing motion, not only on the top and at the sides of the head but also at the back of the head.

The upper wall 44 of the casing 16, so designated when held in the position shown in Figure 1, is provided with flanged internally-threaded plugs or bushings 46 (Figure 3) embedded therein for the reception of screws 48 which also pass through and secure thereto a corrugated stationary base plate 50 of the length of cut guide 14. The stationary plate 50, as its name indicates, has a corrugated outer surface 52 which coats with the similarly-corrugated inner surface 54 on the long arm 56 of an angle bracket 58, the short arm 60 of which is drilled to receive screws 62 threaded into the correspondingly drilled and threaded base 64 of a guide comb 66 having multiple hair-cutting guide tines 68 with pointed ends 69 and extending parallel to the cutting tines 32 and 34 of the

cutting head 36 and in adjustably-spaced relationship therewith.

In order to yieldably hold the corrugated arm 56 of the angle bracket 58 in normally-fixed engagement with the corrugated plate 50, the yieldably-mounted connectors, generally designated 70 (Figure 3), are provided. In order to accommodate the connectors 70, the wall 44 of the casing 16 is provided with sockets 72, preferably four in number although a greater or lesser number may be used if desired. If four connectors 70 are used, they are preferably arranged in a rectangular pattern (Figure 2). The casing 16 is conveniently molded from synthetic plastic material, hence the bushings 46 may be embedded therein during the molding operation and the sockets 72 likewise formed during the molding operation, in a manner well-known to those skilled in the plastic molding art.

The long arm 56 of the angle bracket is in the form of a plate (Figure 2) having its inner side corrugated at 54 and provided with elongated slots 74 preferably equal in number to the number of connectors 70. The slots 74 are preferably arranged in two mutually parallel groups near the opposite edges of the plate arm 56. Mounted in the sockets 72 (Figure 3) are the heads of stud screws 76, the unthreaded shank portions 78 of which slidably engage holes 80 in the stationary plate 50, their threaded reduced diameter end portions 82 passing through the slots 74 and having thumb nuts 84 threaded thereon and extending into the slots 74 (Figure 3). A helical compression spring 86 encircles the shank 78 of each screw 76 between its head and the adjacent surface of the fixed corrugated plate 50 within the socket 72.

In order to facilitate adjustment, a friction pad 88 of serrated or corrugated rubber or other suitable frictional material is secured, as by an adhesive, to the outer surface of the long arm 56 of the angle bracket 58 between the opposite groups of slots 74 so as to prevent slippage while adjusting the length of cut. To do this, the operator holds the hair clipper 12 in one hand with the friction pad 88 facing upward such as in the position shown in Figure 1, places his fingertips or thumb of his other hand on the friction pad 88 and applies a pushing or pulling force parallel to the plate arm 56 sufficient to cause the corrugations on its surface 54 to ride up and over the corrugations on the surface 52 of the fixed plate 50. In this manner he overcomes the thrust of the compression springs 86 and permits the corrugated plate 56 to slide past the corrugated plate 50 and re-engage relatively different mating corrugations thereof. In this way he is enabled to space the tips 69 of the comb tines 68 either closer to or farther away from the nose 38 of the cutter head 36 so as to increase or decrease the length of the hair which will remain after cutting has taken place.

In the use of the invention, with the length of cut thus adjusted, the user grasps the self-operated cut-regulated hair clipper 10 in the manner shown in Figure 1 with the rearward end 40 of the clipper casing 16 resting in his palm P of his hand H and with his thumb T on one side and his fingers F on the other side, his finger tips extending slightly past and around the angle bracket 58. It will, of course, be understood that the clipper 10 may be held in different positions in the hand H, the position shown being convenient for many users. Having started the motor of the clipper by manipulating the switch button 42, the user passes the cutter head 36 over the hair while resting the comb 66 upon the scalp, moving the device 10 with a combing motion over the hair. The comb 66, by being spaced away from the cutters 28 and 30 regulates the length to which the hair is cut.

To cut his hair to different lengths in different places on his head, the user readjusts the comb 66 either nearer to the cutter head 36 or farther away from it, according to whether he wishes his hair to be cut shorter or longer in the particular location. This adjustment is made in the manner described above by pushing or pulling upon

the friction pad 88 to cause the corrugations 54 to yield and slide over the corrugations 52 and re-engage in a new location. In this manner, for example, the hair can be cut shorter at the sides and back of the head than on top, as is usually desired. The short and compact construction of the self-operated cut-regulated hair clipper 10 enables the user to cut his own hair quickly and easily, even the back of the head where it would be impossible for him to use a hand-operated hair clipper or to accurately hold and control the cutting operation of a hair clipper of elongated construction which would not fit between his thumb and fingers or into the palm of his hand. The combing motion by which the self-operated hair clipper 10 is used makes it easy for the unskilled user to cut his own hair to the desired length and in a manner to give a uniform and attractive appearance. It is preferred in using the device to start at the front of the top of the head and move the device backward over the head with a combing motion in order to obtain a satisfactory result.

From Figure 1 it will be observed that the outer end portion 69 of the comb 68 is inclined relatively to the base 64 thereof at substantially the same angle as the cutting tines 32 of the fixed cutter 28. Thus, when the comb 66 is adjusted so that its base 64 is substantially on engagement with the fixed cutter unit 26, its end portion 69 is thereby disposed closely adjacent or in actual engagement with the similarly-inclined end portion of the tines 32 of the fixed cutter 28. This arrangement enables the hair clipper 10 to give the proper taper at the back of the neck and to cut the hair as short as desired, both at the back of the neck and at the sides of the head and temples.

What I claim is:

1. A motor-driven self-operated cut-regulating hair clipper comprising a clipper casing of laterally-elongated shape having a forward end and opposite side walls, a pair of multiple-tined cutters mounted in close proximity to one another on said forward casing end, motor-driven mechanism in said casing operatively connected to one of said cutters for reciprocating one of said cutters relatively to the other cutter in shearing relationship therewith, an angle guide structure having a first arm adjustably secured to one side wall of said casing in a direction lengthwise of said casing and a second arm extending transversely to said first arm, said second arm having a multi-tined guide comb thereon in spaced substantially parallel relationship to said cutters, said first arm having a row of serrations thereon extending lengthwise thereof, and means connected to said casing releasably engageable with said serrations for adjustably securing said first arm to said side wall for adjustment motion lengthwise of said casing.

2. A hair clipper, according to claim 1, wherein said angle guide structure also includes an attachment member secured to said casing, said attachment member and said first arm having interengaging serrations disposed transversely to the lengthwise direction of said casing.

3. A hair clipper, according to claim 2, wherein said securing means includes fasteners yieldingly urging the serrations of said first arm into mating engagement with the serrations of said attachment member.

4. A hair clipper, according to claim 3, wherein said fasteners include resilient elements associated therewith and yieldingly urging said serrations into mating engagement with one another.

5. A hair clipper, according to claim 2, wherein said first arm and casing have cooperating guide means thereon extending lengthwise of said casing and holding said guide comb against tilting out of spaced parallel relationship with said cutters.

6. A hair clipper, according to claim 5, wherein said guide means includes a guide slot arrangement extending lengthwise of said first arm and a plurality of fasteners extending through said guide slot into engagement with

said casing and holding said first arm in adjustable guided engagement with said casing.

7. A hair clipper, according to claim 2, wherein said first arm and said attachment member have cooperating guide means thereon extending lengthwise of said casing 5 and wherein said securing means includes yielding fas-

teners holding said serrations in mating engagement with one another.
